SIZE-DISCHARGE TREATMENT OF FABRICS

George W. Lane, Clifton, N. J., assignor to Van
Vlaanderen Machine Company, Paterson, N. J.,
a corporation of New Jersey

Application October 5, 1938, Serial No. 233,416

4 Claims. (Cl. 8—151)

This invention relates to the production of crepe fabrics, that is, fabrics whose thread constituents are twisted and have size or equivalent adhesive applied thereto (hereinafter termed size) and after the weaving are made to undergo a boil-off or equivalent treatment which discharges the size and leaves the fabric creped. When the fabric contains twisted threads composed in part of rayon and in part of cellulose acetate, the discharge has heretofore been effected only by a manual treatment. That is, the fabrics previously wound in flat form are hung on sticks in a water bath which initially is cold and without any ingredient, as soap, to augment the discharge, and after the fabrics have been left in the bath for some time the latter is gradually heated and the soap added, the fabrics being shifted on the sticks from time to time to insure uniform action by the bath. What is aimed at is to avoid irregular creping which later will occur if the fabric is subjected too abruptly to the discharge action: wherefore the soaking first at low temperature and the ultimate gradual raising of the temperature, with the addition of the soap. By carefully conducting the treatment in this way the creping in fabrics containing twisted threads composed in part of rayon and in part of cellulose acetate can be effected without irregularity in such crepe; but obviously the procedure is necessarily slow and tedious and the labor cost is considerable.

What I aim is to accomplish, in a more simple, expeditious and cheaper way and without irregular creping, the size-discharge from fabrics which (because they contain twisted rayon-cellulose acetate threads or in fact for any other reason) are prone to crepe irregularly unless the discharge is effected subject to such control as will prevent such irregular creping, and to effect such discharge also without the streaking or other distortion in appearance of the fabric which is likely to occur from creases allowed to form therein while undergoing the treatment or from limited contact with parts of the apparatus employed.

Assume existence of a size-discharge bath into which the fabric is to be entered progressively and from which it is ultimately to be withdrawn, and that but only partially submerged in such bath is a rotary drum or equivalent fabric-advancing element arranged with its axis substantially horizontal. I repeatedly rotate the drum in one direction through complete revolutions about said axis and meanwhile progressively deliver the fabric against the exposed portion of

the perimeter of the drum and while such portion still remains wetted by the liquid of the bath, whereby, due to adhesion which ensues between the wetted perimeter of said element and the size-laden fabric, the fabric is conveyed by said element into and through the bath.

In this operation, due to the adhesion between the fabric and the perimeter of the drum, the creping effort is subject to control by the adhesion and, since such is uniform throughout the entire area of the portion of the fabric at any time in contact with said perimeter, the resulting creping is uniform or without that irregularity which would invariably occur if the fabric were simply dipped in the bath with no expedient for maintaining it in extended state.

Usually, though the maximum and hence troublesome creping effort will have already expended itself, it is necessary to continue the fabric in the bath for the purpose of completing the discharge. For this purpose the fabric should be parted from the drum—that is to say, the adhesive union between the fabric and the perimeter of the drum should be disrupted. My invention also contemplates this disrupting or parting step, and in the preferred form of the invention it is effected not only so as to avoid any harm to the fabric but under the surface of the bath, since exposure of the fabric to the atmosphere before the discharge is completed is calculated to create disparities in appearance as between portions of the fabric which may thus become exposed and the remaining portions thereof. In practice, on the fabric being parted from the drum it is delivered onto a travelling conveyor which then conveys it through the bath until the discharge has been completed.

In my procedure it is not to be overlooked that there is a stepping-up, as it were, of the influences which engender the creping. That is to say, the fabric comes to the drum in a relatively cold state, is then somewhat wetted and also heated by the more or less heated moisture on the perimeter of the drum, and finally it attains complete soaking by submersion in the fully heated and otherwise completely active bath itself. There may be shrinkage, in fact considerable, both lengthwise and transversely of the fabric, but this is of course removable later by resort to known procedures. What is important is that the fabric may be made to undergo the discharge treatment progressively and with expedition and that it issues from the treatment with its creping entirely regular in character.

The drawings illustrate the invention more or less diagrammatically.

Figs. 1 and 2 being side elevations of the intake and output ends, respectively, of the apparatus employed when the fabric treated manifests relatively little disposition to crepe irregularly;

Figs. 3 and 4 being similar views of the intake and output ends, respectively, of the apparatus employed when the fabric treated manifests greater disposition to crepe irregularly;

Fig. 5 is a fragmentary side elevation of the drum 2 and the "cascade" device; and

Fig. 6 is a plan of what is shown in Fig. 5.

The fabric *a* comes to the apparatus wound in a roll indicated at position *a'* and consists of a number of pieces stitched together end for end, being usually many yards in length. In winding this roll it is usual to lap outward its inner or starting end so that when the roll is nearing depletion it may be transferred to the position indicated at *a²* and when the end of the lap is uncovered attach such end to the end of the length afforded by a fresh roll placed at position *a'*, all with the purpose of avoiding undue delays in the treatment of the successive fabrics. The roll at either of the positions *a'* and *a²* may therefore be taken as the supply.

Said supply may if desired dip into a bath of plain water at atmospheric temperature and 30 contained in a tank *b*.

Referring, first, to Figs. 1 and 2:

Let *1* be a vat containing the discharge liquid bath, whose surface or level is indicated at *x*. A drum *2* with its axis horizontal and journaled in any suitable support (not shown) exists only partially submerged in the bath. The drum is to receive against its perimeter and advance the fabric, being constantly rotated through complete revolutions and usually at a constant speed 35 in respect to the fabric at any time being treated; its direction of rotation is as per the arrow. The fabric extends from the supply in flat state around a spreader bar *3*, then between a small drum *4* and a nip-roll *5*, and then around a roll *6* so positioned that the fabric in being advanced by the drum *2* travels in contact therewith for an appreciable circumferential extent before it enters the liquid at what may be termed the approach side of the drum. At the opposite or discharge 50 side of the drum is what I term a "cascade" device, being a trough *7* which inclines downwardly toward said side, its lower end being sufficiently close to the drum's periphery so that liquid debouching from the trough will part the fabric at the discharge side of the drum from its perimeter, in this example, while the fabric is still submerged. This device forms the spout of a tank *8* which may receive liquid from the vat via a pump *9* and a pipe *10*. It is not material what 55 drives the drum, but I show diagrammatically a motor *11* which, through a variable-speed drive *12*, as a so-called Reeves drive, drives a reduction-box *13* whose output gear *14* meshes with a gear *15* of the drum.

Rotation of the drum *2* involves advance of the fabric, and in its rotation its perimeter carries from the bath some of the liquid and the thus wetted exposed portion of its perimeter serves, when the fabric is progressively fed thereto by roll *6*, to obtain a certain grip by adhesion on the sized fabric which maintains it constantly in a state of conformity by adhesion to the surface of the drum's perimeter. In this example, the fabric is assumed to have such relatively weak creping effort that by the time it has about passed

through the liquid under the drum, irregularity of creping incident to further exposure to the bath will not ensue. Meanwhile the cascade is active, and as fast as the fabric comes within the influence of the liquid current it directs downwardly against or close to the drum's perimeter, the fabric is parted by the cascade from such perimeter, such taking place here below the liquid level, and is delivered onto an endless conveyer *16* extending around drums *17*.

Referring to Figs. 3 and 4: Here the apparatus is designed for performance of my method when the character of the fabric is such, as by being heavy and compactly woven, that the tendency toward irregular creping endures longer after the 15 fabric enters the bath than is heretofore assumed. The parts *a'* and *a²* and *1* to *17* are all the same as before. In addition to drum *2* there are the drums *18* and *19* both suitably supported with their axes parallel with that of drum *2*, and drum *18* partly 20 submerged in the bath the same as drum *2* but drum *19* elevated above the bath. These three drums are rotated as per the arrows and in unison through suitable transmissions diagrammatically indicated at *20*. In addition to the cascade device *7* for drum *2* there is a cascade device *21* for drum *18*, *22* being its supply tank; there are also cascade devices *23* discharging in opposite directions onto drum *19*, being supplied by a tank *24*. Pipe *10* has extensions *10a* and *10b* leading 30 to tanks *22* and *24*.

In this case the period in which the fabric is held extended both transversely and lengthwise is obviously increased by the presence of the three drums and the adhesion of the sized fabric to their 35 perimeters. By the cascade devices *23* the fabric is kept wetted while travelling over the drum *19*, the moisture incidentally insuring the desired adhesion between the fabric and drum.

Since allowance for lengthwise shrinkage of the 40 fabric should be provided for, the portions of the transmissions *20* which connect drums *2* and *18* with drum *19* may each be of the belt and cone-pulley type.

How the conveyer *16* is driven is immaterial. 45 In Figs. 1 and 2 it is assumed to be driven sufficiently slowly so that the fabric accumulates thereon in more or less pleated or undulated state as shown at *a³*. In Figs. 3 and 4 it is shown driven at a rate about the same as that at which the 50 fabric is delivered to it, as by a motor *25* driving a variable-speed drive *26*, in turn driving a reduction-box *27*, from which one of rotary supports *17* for the conveyer may be driven through a suitable transmission *28*.

At *29* is a roller under which the fabric passes on its way to a delivery drum *30*. By training the fabric only around the drum *2*, the treatment with this apparatus may be conducted the same as with the apparatus shown in Figs. 1 and 2.

In the appended claims I use the term "size" or "sized" with the intent that they shall be construed to include any adhesive suitable for maintaining the threads of the fabric in twisted state.

My invention, insofar as the prevention of 65 irregular creping is concerned, is a matter of opposing shrinkage of the fabric for a time after it enters the discharge bath. According to the invention in its broad aspect the fabric is progressively entered into and passed through the 70 bath and meanwhile, with respect to a zone through which it travels and whose anterior side (as in the plane *y*—*y* in Fig. 5) is coincident with the entry of the fabric into the bath, shrinkage of the fabric is opposed uniformly throughout

the whole area thereof which is at any time within said zone.

Having fully described my invention, what I claim is:

5. 1. The method of discharging the size from a sized fabric which consists in repeatedly completely revolving in one direction about its own substantially horizontal axis a rotary fabric-advancing element arranged in a state of but partial submersion in a size-discharge bath, meanwhile progressively delivering the fabric against and into adhering relation to the exposed portion of the perimeter of said element while such portion still remains wetted by the liquid of the bath and thereupon maintaining the fabric substantially uninterruptedly in such relation until it enters the bath, and diverting the fabric from the perimeter of said element at a position under the surface of the bath. 10
10. 2. The method of discharging the size from a sized fabric which consists in repeatedly completely revolving in one direction about its own substantially horizontal axis a rotary fabric-advancing element arranged in a state of but partial submersion to a size-discharge bath, meanwhile progressively delivering the fabric against and into adhering relation to the exposed portion of the perimeter of said element while such portion still remains wetted by the liquid of the bath and thereupon maintaining the fabric substantially uninterruptedly in such relation until it enters the bath, and meanwhile progressively diverting the fabric from the perimeter of said element at a position under the surface of the bath. 15
15. 3. The method of discharging the size from a sized fabric which consists in repeatedly completely revolving in one direction about its own substantially horizontal axis a rotary fabric-advancing element arranged in a state of but partial submersion to a size-discharge bath, meanwhile progressively delivering the fabric against and into adhering relation to the exposed portion of the perimeter of said element while such portion still remains wetted by the liquid of the bath and thereupon maintaining the fabric substantially uninterruptedly in such relation until it enters the bath, and directing a liquid current between the fabric and the perimeter of said element and thereby diverting the 20
20. 4. The hereindescribed apparatus including a size-discharge-bath-containing vat, rotary elements arranged with their axes substantially horizontal and one of which is partially submerged in and the other extends above the surface of the bath, means coupling said elements together for conjoint rotation, means coactive with said elements to hold the sized fabric to be treated, when trained under the first and over 25 the second element, in flat state and in direct contact with the peripheries of both elements, and means to deliver heated size-discharge liquid onto the portion of the fabric extending over the second element, whereby to effect discharge of 30 size from the fabric when said elements are so rotated that the first element advances the fabric to the second element and meanwhile opposes shrinkage of the fabric. 35
